INTERLOCKING SYSTEM FOR RAILROADS

Robert M. Phinney, Brighton, N. Y., assignor to
General Railway Signal Company, Rochester,
N. Y.

Application August 12, 1936, Serial No. 95,590
Renewed September 25, 1937

42 Claims. (Cl. 246—134)

This invention relates to electric interlocking systems for railroads, and more particularly pertains to an interlocking system of the entrance-exit type.

The interlocking system of the present invention contemplates a miniature track diagram located in the central control office which corresponds to the actual track layout in the field. Suitable initiating and completing buttons or levers are located on the miniature track diagram for the end of each route. The operation of an initiating button at the entrance to a route together with the contemporaneous actuation of the completion button for the exit end of that route, compositely controls all of the individual track switches included in that route and clears the signal for such route when all of the track switches have properly responded.

One of the objects of the present invention is to provide for an interlock between the entrance and exit buttons in such a way that only one route from a group of conflicting routes may be established at any one time. This is accomplished by means of electric circuits and relays in such a way that the number of relays required is increased the same amount for the addition of each switch and crossover in the track layout for that group, irrespective of the arrangement of the layout.

Another object of the present invention is to provide for composite route indications on the miniature track diagram which are particularly adaptable to an entrance-exit type interlocking system.

Other objects, purposes and characteristic features of the present invention will be in part obvious from the accompanying drawings, and in part pointed out as the description of the invention progresses.

In describing the invention in detail, reference will be made to the accompanying drawings, in which like letters in the reference characters designate similar functions or relationships with the distinctiveness between such reference characters provided by the use of distinctive preceding numerals; in which like preceding numerals in the reference characters when applied to different letters represent the inclusion of such devices within a particular group; and in which:

Figs. 1 and 2 when placed side by side diagrammatically illustrate the control office and field station apparatus comprising an interlocking system of the present invention as applied to a single crossover;

Fig. 3 illustrates diagrammatically the inter-

lock between a plurality of switch control relays in a complicated track layout involving crossovers and single switches; and

Fig. 4 illustrates diagrammatically a typical modified form of circuit control for the entrance and exit buttons on the control panel.

For the purpose of simplifying the illustration and facilitating in the explanation thereof, the conventional parts and circuits constituting the embodiment of the invention have been shown diagrammatically and certain conventional illustrations have been employed, the drawings having been made more with the idea of making clear the purposes and principles of the present invention together with its mode of operation, than with the idea of illustrating the specific construction and arrangement of parts that would probably be employed in practice.

The various relays and their contacts are illustrated in a conventional manner and symbols are employed to indicate connections to the terminals of batteries or other suitable sources of electric current supply instead of showing all of the wiring connections to such terminals.

The symbols (+) and (—) are employed to indicate the positive and negative terminals respectively of suitable batteries or other sources of electric energy; and those terminals with which these symbols are used are presumed to have current flowing from the positive terminal designated (+) to the negative terminal designated (—).

The symbols employed with any one circuit are considered to designate the terminals of the same battery or other suitable source, but it is to be understood that as many separate sources may be provided as found necessary, or as many sources may be combined into a single source as found expedient in the practice of the invention.

If alternating current is employed, then the symbols should be considered to represent the instantaneous relative polarities of the respective terminals.

Where groups of devices are referred to in a general way, such devices will be designated by the letters or preceding numerals characteristic of such groups instead of mentioning each specific reference character of that group of devices,

APPARATUS

Track layout.—In Fig. 2 of the accompanying drawings, the invention has been shown applied to a track layout including a stretch of double track connected by a crossover having switch points TSA and TSB. The stretch of double

track includes a main line extending from a signal 3 to a signal 4, and another main line extending from a signal 5 to a signal 6. Signals 3 and 6 govern the traffic over the crossover as well as over the main line tracks with which they are associated.

Inasmuch as the opposite ends of a crossover are usually operated at the same time, the crossover may be considered as operated by a single switch machine SM, which may be of any suitable type, such for example, as disclosed in the patent to W. K. Howe, Patent No. 1,466,903, dated September 4, 1923. However, two switch machines SM may be employed, if desired, all within the scope of the present invention.

It should also be understood that the invention is not limited, as thus shown, to the control of a crossover and signals of this chosen layout, but may be extended for any desired number of switches and signals and may be readily applied to all types of track layouts found in interlocking plants, and when thus applied to more complicated track layouts reference should be made to Fig. 3 which illustrates the manner in which the features of the present invention illustrated in Figs. 1 and 2 should be applied to a complex track layout. The manner in which the present invention applies to a single track switch instead of a crossover, will be pointed out hereinafter by mentioning those parts of the present disclosure which may be readily omitted when only a single turnout switch is controlled by a system constructed in accordance with the present invention.

The signals 3, 4, 5 and 6 are assumed to be color light signals giving the usual indications of green for clear and red for danger or stop, and yellow, if an added indication is desired, for caution. However, these signals may be of the search light type, the semaphore type, or any other suitable type instead of the particular type chosen for the embodiment of the present invention.

The track layout has been shown as divided into two track circuits 8 and 9 by insulated joints, which track circuits are provided with the usual track batteries and track relays of which track relays 8T and 9T have been shown. These normally energized track circuits are wired in the usual manner to provide for fouling protection and to provide for the insulation of the track switches, such details of wiring having been omitted for the sake of simplicity in the disclosure.

The crossover, including the track switches TSA and TSB, is shown as having a single switch position repeating relay WP of the usual polar neutral type. This relay WP is energized with one polarity or the other in accordance with the normal and reverse locked positions of the track switches TSA and TSB with the switch machine SM in corresponding positions, and is deenergized whenever the track switches are unlocked or are in operation. The polarized circuit for controlling such a switch position repeating relay is governed through the medium of a point detector contact mechanism such as shown for example in the patent to C. S. Bushnell, Patent No. 1,517,236, dated November 25, 1924, it being understood that there would of course be two such mechanisms when two switch machines SM are employed.

Control machine.—A suitable control machine is located in the central office and is provided with a control panel on which a track diagram

is constructed corresponding to the actual track layout in the field. The construction of this track diagram is such that the trackway is made up of molded glass sections, or other suitable transparent material, which form the trackway. These sections are distinctively colored for the different facts which their illumination are assigned to indicate.

More specifically, the sections 8TK and 9TK which take locations on the diagram corresponding to the points of the switches TSA and TSB, are preferably of amber color so that when their respective indicator lamps 8TK¹ and 9TK¹ are illuminated, a distinctive indication of track occupancy is indicated to the operator. The sections NKA, RK and NKB are preferably red in color so that when their respective indicator lamps NKA¹, RK¹ and NKB¹ are illuminated, an indication is given to the operator which is distinctive from the other conditions of illumination on the panel. These indicator sections NKA, RK and NKB represent the routes set up, when illuminated, and are unilluminated so long as such routes are free to be included in newly proposed routes. The particular significance of these indicators as cleared route designators to warn the operator against endeavoring to set up conflicting routes will be more readily apparent in the description of the operation of the system.

Between certain illuminated trackway sections on the diagram and at route determining points represented in the track layout, are suitable entrance and exit buttons which control the setting up of routes and the clearing of the signals for such routes. An entrance button NB is provided for each of the signal locations, such as entrance buttons 3NB, 4NB, 5NB and 6NB for the respective signals 3, 4, 5 and 6. An exit button XB is provided for the end of each route, shown specifically as exit buttons 3XB, 4XB, 5XB and 6XB. It is to be understood, that the ends of the routes may or may not correspond to the locations of the exit buttons on the miniature track diagram, as a route is usually considered to extend from one particular signal to the next signal governing traffic in the same direction or to some arbitrarily chosen point.

Each entrance button NB is in the form of a knob which is rotatable 90° from a normal position to an operated position. The 90° rotation of a button NB, such as button 3NB, in a clockwise direction closes its associated contacts, and remains in that position to keep its contacts closed until it is manually restored to its normal position. For the purpose of conserving space on the control panel, the exit buttons XB are located within the entrance buttons NB. These exit buttons XB are of the self-restoring push button type, and to further conserve space have within their centers, the signal indicators SK which, when illuminated, indicate the cleared condition of their corresponding signals. Thus, the indicators 3SK, 4SK, 5SK and 6SK are provided to indicate the clear condition of their respective signals 3, 4, 5 and 6, all of which is accomplished through means not shown in the present disclosure for the sake of simplicity, although reference may be made to the application of S. N. Wight, Ser. No. 69,905, filed March 20, 1936, for the details of such control. It should also be noted, that the construction of the entrance-exit and signal indicator combination NB—XB—SK has been shown in Fig. 10 of the above mentioned application of S. N. Wight, Ser.

No. 69,905. The signal indicators SK are preferably green in color when illuminated.

Although it is preferably desirable that the trackway indicators TK, RK and NK give a dark board appearance, when unilluminated, it is also desirable that these indicator sections and intervening marked (or dummy) sections on the panel, clearly indicate the track layout even while all of the indicators are unilluminated, yet at the same time provide distinctiveness between the different kinds of indicators. The route indicator sections are provided with dark spots for the insulated joints or ends of the track circuits, which has been more particularly illustrated for the indicator RK. It is of course apparent that the insulated joints do not need to be illustrated when they fall opposite a signal location involving an entrance and/or exit button on the control panel.

An emergency switch control lever SML is also provided to control the operation of the switch machine SM under certain emergency conditions hereinafter pointed out in detail. This emergency switch control lever may be suitably located upon the control panel, but is preferably located on the back of the control machine, because of the fact that such lever is only used for emergency conditions. Associated with the lever SML is an indicator lamp COR, which is illuminated whenever the crossover, including switches TSA and TSB, is in mid-stroke or is out of correspondence with its switch machine control as set up either by the composite entrance-exit route control or by the emergency switch control lever SML.

System apparatus.—The entrance buttons NB and exit buttons XB are respectively shown as connected to the contacts which they operate by dotted lines so as to make their relationships readily apparent. Associated with each entrance button NB is an entrance relay NR; and similarly associated with each exit button XB is an exit relay XR. The entrance relay NR and the exit relay XR for each signal location are interlocked as will be described hereinafter.

The entrance relay NR for one end of a route and the exit relay XR for the opposite end of that route jointly control the positioning of the proper switch control relays for the switches in that route. For the crossover of Fig. 2, switch relays WNA, WR and WNB are provided to be thus controlled by the entrance and exit relays NR and XR, which neutral switch controlling relays in turn govern the operation of the switch machine SM through the two position polarized relay WZ. Associated with the control for each switch machine is a lock relay L which prevents the operation of the switch machine SM when it is unsafe for the track switches TSA and TSB to be operated.

Relays NCR and RCR are provided to indicate when the track switches TSA and TSB are in correspondence with their control as will be pointed out hereinafter.

A signal control relay G is provided for each signal for causing that signal to indicate clear or stop. These signal relays include relays 3G, 4G, 5G and 6G for their respective signals 3, 4, 5 and 6, and are selectively controlled in accordance with the position and locked condition of the track switch and in accordance with the condition of the entrance and exit relays NR and XR, as will be hereinafter described.

A signals at stop relay M is energized when all of the signals 3, 4, 5 and 6 are at stop, and is

deenergized whenever any one of these signals is at clear.

In an interlocking system, there is usually suitable approach locking and route locking means associated with the signals and switch control means, and the system of the present invention is contemplated as having applied thereto any suitable approach and route locking means as desired in accordance with the practical operation of trains for any particular installation, but for the purpose of illustration, directional stick relays 8ES, 8WS, 9ES and 9WS are associated with their respective track circuits 8 and 9, as indicated by their preceding numerals, to provide what is termed rear release route locking, all of which has been disclosed in the prior application of C. F. Stoltz, Ser. No. 402,527, filed October 25, 1929, to which reference may be made for the details of control for such relays.

It is considered sufficient for an understanding of the present invention to know that the relay 8ES is deenergized when the signal 3 is cleared and is maintained deenergized, although the signal is returned to stop, so long as a train is on the track circuit 8, but during such deenergized condition of the relay 8ES, the relay 8WS remains picked up. Similarly, the relay 8WS is deenergized when the signal 4 is cleared and remains deenergized so long as a train is on the track circuit 8, although the signal 4 is returned to stop, but during such deenergized condition of the relay 8WS, the relay 8ES remains picked up.

Likewise, the relay 9ES is deenergized whenever the signal 5 is cleared and is maintained deenergized, although the signal is returned to stop, so long as a train is on the track circuit 9, but during such deenergized condition of the relay 9ES, the relay 9WS remains picked up. Similarly, the relay 9WS is deenergized whenever the signal 6 is cleared and remains deenergized so long as a train is on the track circuit 9, although the signal 6 is restored to stop, but during such deenergized condition of the relay 9WS, the relay 9ES remains picked up.

It is also noted in this connection, that when the track switches TSA and TSB are in reverse positions to allow traffic to pass over the crossover and the signal 3 is cleared, both the relays 8ES and 9ES are deenergized; and similarly, when the signal 6 is cleared for traffic in an opposite direction over the crossover, both the relays 9WS and 8WS are deenergized.

It is believed that the remaining features of the present invention will best be understood by considering the detailed operation of the system.

Normal conditions.—Although the track switches TSA and TSB are usually left in their last operated positions under normal operating conditions, they have been shown in positions for the passage of main line traffic. The signals are considered to be normally "at stop" with the lower or red indicator of each signal normally illuminated, unless approach lighting features are employed in accordance with the usual practices.

With the track sections 8 and 9 unoccupied, the respective track relays 8T and 9T are of course normally picked up.

The lock relay L, the directional stick relays 8ES, 8WS, 9ES and 9WS, the signals "at stop" relay M, and the relay WP, are normally energized, but the circuits and various conditions governing these relays will be discussed in detail hereinafter.

All of the indicators on the control panel are normally deenergized to provide what has been conveniently termed a "normally dark board."

Entrance-exit route interlock.—When the operator desires to set up a route from the signal 3 to the signal 4, for example, he rotates the entrance button 3NB in a clockwise direction to its operated position which closes a circuit for the entrance relay 3NR from (+), through a circuit including closed lever contact 15, back contact 16 of exit relay 3XR, winding of relay 3NR, to (-). This energizing circuit for the entrance relay 3NR remains closed so long as the entrance button 3NB is left in its operated position. The picking up of the contacts of the entrance relay 3NR also prevents the operation of its associated exit relay 3XR by disconnecting (-) at back contact 17 from the right hand terminal of relay 3XR.

After actuating the entrance button 3NB, the operator then glances along the miniature track-way and finds that there are no indicators illuminated between such entrance button 3NB and the exit button 4XB which designates the end of the route which he desires to set up. The operator then actuates the exit button 4XB which closes a pick up circuit for the exit relay 4XR from (+), through a circuit including back contact 18 of exit button 4XB, winding of exit relay 4XR, back contact 19 of entrance relay 4NR, to (-).

The conditions under which the illumination of an indicator in the trackway advises the operator against the establishment of a route will be discussed in detail after a description of the specific control for the various indicators has been given.

The contemporaneous operation of the entrance relay 3NR and the exit relay 4XR closes an energizing circuit for the switch control relay WNA from (+), through a circuit including front contact 20 of relay 3NR, lower winding of relay WNA, back contact 21 of relay WR, back contact 22 of relay 4NR, front contact 23 of relay 4XR, to (-). The current which flows in this circuit causes the relay WNA to pick up its contacts, and to remain picked up so long as this circuit is closed.

When the relay WNA responds, a stick circuit is closed for the relay 4XR from (+), through a circuit including front contact 24 of relay 3NR, front contact 25 of relay WNA, back contact 26 of relay 4NR, front contact 27 of relay 4XR, windings of relay 4XR, back contact 19 of relay 4NR, to (-).

As soon as this stick circuit is closed, the operator may then release the exit button 4XB and the exit relay 4XR remains picked up dependent upon the restoration of the entrance button 3NB. The operator is advised as to the time at which he may release the exit button 4XB by the illumination of the route indicator section NKA, because this indicator section becomes illuminated immediately upon the picking up of the relay WNA. The lamp NKA¹ is energized by a circuit closed from (+), through a circuit including front contact 28 of relay WNA, bus wire 73, indicator lamp NKA¹, to (-).

It will be obvious that the opening of back contact 140 of relay 4XR will prevent the accidental energization of relay 4NR. Also, the picking up of the contacts of the relay WNA prevents a conflicting route from being established by reason of the opening of back contacts

29 and 30, which feature will be described in detail hereinafter.

The picking up of the contacts of the relay WNA effects the control of the switch machine by energizing the relay WZ to a normal position by a circuit closed from (+), through a circuit including front contact 31 of relay L, front contact 32 of relay 9T, front contact 33 of relay 8T, wire 34, front contact 35 of relay WNA, wire 36, lower winding of relay WZ, to (-). The current which flows in this circuit actuates the polar contacts of relay WZ to the right hand normal positions in which energy is supplied to the switch machine SM by a circuit closed from (+), through a circuit including front contact 37 of relay 8T, front contact 38 of relay 9T, front contact 39 of relay L, polar contact 40 of relay WZ in a right hand position, through the switch machine SM, to (-). The switch machine SM, thus energized, causes the operation of the track switches TSA and TSB to normal positions which is repeated by the relay WP. When the relay WP assumes a normal energized position, the normal correspondence relay NCR is energized by a circuit closed from (+), through a circuit including front contact 41 of relay WNA, wire 42, windings of relay NCR, back contact 43 of relay RCR, polar contact 44 of relay WP in a right hand position, front contact 45 of relay WP, to (-).

While all of the switch control relays WNA, WR and WNB for this switch machine SM are deenergized, a pick up circuit is closed for the relay L from (+), through a circuit including back contact 46 of relay WNA, back contact 47 of relay WR, back contact 48 of relay NCR, back contact 50 of relay RCR, front contact 51 of relay 8T, front contact 52 of relay 9T, front contact 53 of relay 8ES, front contact 54 of relay 9ES, front contact 55 of relay 9ES, front contact 56 of relay 9WS, front contact 57 of relay M, windings of relay L, to (-).

Upon the picking up of the relay WNA, this pick up circuit just traced for the relay L is broken at back contact 41, but the relay L remains picked up by reason of its stick circuit which is closed from (+), through a circuit including front contact 58 which applies energy to the heel of contact 49 and thence through the remainder of the pick up circuit for the relay L.

Thus, upon the picking up of the relay NCR, and the opening of its back contact 49, which is included in both the pick up and stick circuits for the relay L, the relay L is caused to drop away. If the crossover TS is required to be operated, then the relay L does not drop away until the crossover reaches a position in correspondence with the switch control relays WNA, WR or WNB. But, if the crossover TS is already in the position required for the route to be established, then the picking up of the correspondence relay for that route occurs immediately following the picking up of a switch control relay and the relay L immediately drops away.

In the particular case under consideration, the relay NCR picks up back contact 49 and the relay L drops away, so that open front contact 31 prevents further control of the relay WZ and so that open front contact 39 removes all energy from the switch machine SM.

When the lock relay L drops away, indicating the completing of the route so far as the position of the track switch TSA is concerned, a circuit is closed for energizing the signal 3G

from (+), through a circuit including front contact 59 of relay 4XR, wire 60, back contact 61 of relay L, front contact 62 of relay NCR, wire 63, back contact 64 of relay 3XR, front contact 65 of relay 3NR, wire 66, windings of relay 3G, to (-).

The picking up of the relay 3G changes the indication of the signal 3 from stop to clear allowing the passage of a train over the track-way.

The relay M is deenergized by reason of the opening of back contact 67 of relay 3G, which relay M is normally energized by a circuit closed from (+), through a circuit including back contact 67 of relay 3G, back contact 68 of relay 4G, back contact 69 of relay 6G, back contact 70 of relay 5G, windings of relay M, to (-).

The deenergization of the relay M further opens the pick up and stick circuits of lock relay L at open front contact 57. The energization of the signal relay 3G also effects the deenergization of the route locking relay 8ES which further opens the pick up and stick circuits for the lock relay L at front contact 53.

The closure of back contact 71 of relay 8ES closes another energizing circuit for the normal route indicator lamp NKA¹ from (+), through a circuit including back contact 71 of relay 8ES, polar contact 72 of relay WP in a right hand position, bus wire 73, indicator lamp NKA¹, to (-).

Let us assume that the train accepts the signal 3 and passes over the track circuit 8. The occupied condition of the track circuit 8 deenergizes the track relay 8T which through back contact 37 also supplies (+) energy to the wire 73 for energizing the indicator lamp NKA¹, and which through back contact 74 supplies energy from (+) to the wire 75 for energizing the track indicator lamp 8TK¹. This illuminates the track indicator section 8TK advising the operator that the train has accepted the route.

If the signals are made semi-automatic, then the occupied condition of the route will cause the signal 3 to go to stop unilluminating the signal indicator 3SK, but irrespective of whether the signal 3 is put to stop automatically by the presence of a train or by manual manipulation of the entrance button 3NB to a normal position, the route indicator NKA remains illuminated so long as the train is on the track circuit 8. This is because the back contact 37 supplies energy to the wire 73 through polar contact 72 of the relay WP, although the front contact 28 of the relay WNA may be open. In other words, the occupied condition of a track circuit subsequent to the clearing of a route in which such track circuit is included, causes its corresponding route section indicator to continue to be illuminated, as well as to cause the contemporaneous illumination of the associated track indicator, such as indicator 8TK¹. If the route includes a large number of track sections, then there is a directional stick relay, such as relay 8ES, for each of the track sections, which directional stick relays for those track sections in advance of the track section on which the train is located, are held deenergized by the presence of the train in the route although the governing signal is returned to stop. Thus, the respective route indicators, such as NKA for example, are maintained illuminated in advance of the train by reason of the back contacts of the directional stick relays such as contact 71 of the relay 8ES, for example.

In other words, for a large or complicated track layout, where there are a plurality of track

circuits in a route, each track circuit is provided with its directional stick relay which when held deenergized by a train passing through the route, maintains its respective route indicator illuminated. But, as the train passes through the route, the route indicators for the track sections in the rear of the train become successively unilluminated. The track indicators TK are illuminated only when their respective sections are occupied by a train.

10 *Interlock against conflicting route.*—Let us assume that the route from signal 3 to the signal 4 has been set up, as above described, that the entrance button 3NB is in an operated position holding the relays 3NR, 4XR and WNA picked up, and that the operator unadvisedly proposes to set up a conflicting route from signal 6 to the signal 3.

Under such conditions, the operator rotates the 20 entrance button 6NB in a counter-clockwise direction to an operated position. He then operates the exit button 3XB disregarding the illumination of the normal route lock lamp for that crossover NKA. The actuation of the entrance button 6NB closes a pick up circuit for the relay 6NR from (+), through a circuit including contact 88 of entrance button 6NB, back contact 81 of relay 6XR, windings of relay 6NR, to (-). The actuation of the exit button 3XB accomplishes no useful purpose because the closure of 30 back contact 82 of this exit button cannot energize the relay 3XR because of the open back contact 17 of the relay 3NR. It will be noted that the front contact 29 supplies positive potential 35 (+) to the left hand terminal of the relay WNA and would also supply such energy to the left hand terminal of the relay WR, but this is prevented with the relay WNA picked up opening back contact 30. Therefore, the establishment of 40 a conflicting route is effectively prevented.

Electric lock equivalent.—Let us now assume that the operator has restored to stop the route from the signal 3 to the signal 4 by returning the entrance button 3NB to a normal position, but 45 that the train which accepted the clear signal 3 is still on the track section 8 (or some other track section included within the route when a more complicated track layout is involved), so that the lock relay L is maintained deenergized. Then assume that the operator successively actuates the entrance button 6NB and the exit button 3XB. The relay 6NR is picked up. The relay 3XR is picked up by a circuit closed from (+), through a circuit including back contact 82 of 55 the exit button 3XB, windings of relay 3XR, back contact 17 of relay 3NR, to (-).

When the relay 3XR picks up a circuit is closed for the relay WR from (+), through a circuit including front contact 84 of relay 3XR, back contact 20 of relay 3NR, back contact 33 of relay WNA, lower winding of relay WR, back contact 85 of relay WNB, front contact 83 of relay 6NR, to (-).

65 The closure of front contact 86 of relay WR completes a stick circuit for the relay 3XR from (+), through a circuit including front contact 87 of relay 6NR, back contact 88 of relay WNB, front contact 86 of relay WR, back contact 25 of relay WNA, back contact 24 of relay 3NR, front contact 89 of relay 3XR, windings of relay 3XR, back contact 17 of relay 3NR, to (-). Thus, the relays 3XR and WR are maintained energized until the entrance button 6NB is restored to a normal position.

The closure of front contact 46 of the relay

WR cannot energize the relay RCR because the polar contact 44 of the relay WP is in a normal position; while the closure of front contact 99 of the relay WR cannot energize the relay WZ because the lock relay L is dropped away due to the occupied condition of the track circuit 8 (or some other track circuit in the route holding the associated route stick relays deenergized, which in turn hold relay L deenergized).

Even if the train in such route from signal 3 to signal 4 passes out of the route allowing the track relays and directional stick relays for that route to be picked up, the switch controlling relay WZ will not be energized upon such departure as the lock relay L cannot be picked up until all of the switch controlling relays WNA, WR and WNB are dropped away while the track switches TSA and TSB may be safely operated.

In other words, it is necessary for the operator to return the entrance button 6NB to its normal position dropping away the relays 6NR, 3XR and WR and again actuating the entrance button 6NB and the exit button 3XB to pick up the relays, as above described. While the relay WR is thus deenergized, the pick up circuit for the lock relay L is closed for a sufficient time through the back contacts 41, 46 and 47 of the relays WNA, WR, and WNB to pick up relay L and render it dependent upon its stick circuit so that upon the subsequent picking up of the relay WR, the front contact 90 closes a reverse energizing circuit for the switch controlling relay WZ from (+), through a circuit including front contact 31 of the relay L, front contact 32 of relay 9T, front contact 33 of relay 8T, wire 34, front contact 90 of relay WR, wire 91, upper winding of the relay WZ, to (-). As the upper and lower windings of the relay WZ are differentially connected, the current which flows in this circuit through the upper winding of the relay WZ causes the actuation of its polar contacts to left hand position. The reverse operating circuit for the switch machine SM is now closed from (+), through a circuit including front contact 37 of relay 8T, front contact 38 of relay 9T, front contact 39 of relay L, polar contact 40 in a left hand position, through the switch machine SM, to (-). During this reverse operation of the switch machine SM, the relays NCR and RCR are both deenergized, so that the lock relay L is maintained energized through its stick circuit including back contacts 49 and 50.

As soon as the track switches TSA and TSB are operated to their reverse locked positions by the switch machine SM, which is repeated by the relay WP, an energizing circuit is closed for the reverse correspondence relay RCR, from (+), through a circuit including back contact 41 of relay WNA, front contact 46 of relay WR, wire 92, back contact 93 of relay NCR, windings of relay RCR, polar contact 44 of relay WP in a left hand position, front contact 45 of relay WP, to (-).

This picking up of the relay RCR and opening of back contact 50 deenergizes the lock relay L, thereby effectively preventing further operation of the switch control relay WZ and the switch machine SM at contacts 31 and 39. The drop away of relay L also closes the signal clearing circuit for the signal relay 6G from (+), through a circuit including front contact 64 of relay 3XR, wire 63, back contact 62 of relay NCR, front contact 94 of relay RCR, back contact 95 of relay NCR, back contact 96 of relay L, wire 97, back contact 98 of relay 6XR, front contact 99

of relay 6NR, wire 100, windings of relay 6G, to (-).

The energization of the relay 6G changes the indication of the signal 6 from stop to clear for the passage of a train over the crossover, in a similar manner as described for the route from signal 3 to signal 4.

This route may be put to stop as soon as the train enters such route either automatically or by the manual manipulation of the entrance button 6NB to its normal stop position. Even though the signal 6 may be automatically put to stop, the entrance button 6NB must be manually restored.

It may be well to note here that during every operation of the track switches TSA and TSB, or any time that they are out of correspondence with their control set up in relays WNA, WR and WNB, the correspondence lamp COR is illuminated. For example, with either or both of the relays WNA and WNB picked up, (+) potential is supplied to the wire 42 in an obvious manner so that with polar contact 101 in a reverse position, the correspondence lamp COR is energized over wire 102. Similarly, whenever the relays WR is picked up, (+) energy is supplied to the wire 92 so that with the polar contact 101 of relay WP in a right hand position the correspondence lamp COR is energized over the wire 102.

As soon as the reverse relay WR responds to its entrance-exit control, as above explained, the reverse indicator RK is illuminated by reason of the energization of its indicating lamp RK¹ through front contact 103 over the bus wire 104, and is maintained energized so long as the train is on either or both of the track sections 8 and 9 by reason of the supply of energy from (+) through back contact 105 of track relay 9T, polar contact 106 in a left hand position to the bus wire 104, and also by reason of the supply of energy from (+) through the back contact 37 of relay 8T, polar contact 72 in a left hand position to the bus wire 104. Also, the contacts 107 and 108 of the relays 8WS and 9WS are effective so long as the crossover is in advance of the train in the route to supply energy through polar contacts 72 and 106 respectively left hand positions to the wire 104 for the lamp RK¹.

The occupied condition of the track circuit 9 closes back contact 109 of track relay 9T and energizes the indicator 9TK¹ over the wire 110 to illuminate the track section indicator 9TK.

Establishing a parallel route.—Assuming that the route from the signal 3 to the signal 4 has been set up, as above described, any number of parallel or non-conflicting routes can be established, as for example, the establishment of a route from the signal 5 to the signal 6. To do this, the operator actuates the entrance button 5NB to an operated position which closes a circuit for the entrance relay 5NR from (+), through a circuit including contact 111 in an operated position, back contact 112 of relay 5XR, windings of relay 5NR, to (-). The operator then actuates the exit button 6XB which closes a pick up circuit for relay 6XR from (+), through a circuit including back contact 113 of exit button 6XB, windings of relay 6XR, back contact 114 of relay 6NR, to (-).

The contemporaneous energization of the relays 5NR and 6XR closes an energizing circuit for the relay WNB from (+), through a circuit including front contact 115 of relay 5NR, back contact 116 of relay WR, lower winding of relay

WNB, back contact 83 of relay 6NR, front contact 117 of relay 6XR, to (-).

The energization of the relay WNB closes front contact 47 to energize the relay NCR and closes front contact 118 to energize relay WZ, but having assumed that relay NCR is already energized by front contact 41 and that relay WZ has been positioned through front contact 35, no change occurs. But if the track switch were not in a normal position and a route were not established from the signal 3 to the signal 4, then front contact 118 of relay WNB would cause the energization of the relay WZ through its lower winding by a circuit similar to the one pointed out for the relay WNA, as the contacts 35 and 118 are in multiple.

Irrespective of whether or not there is a route set up from the signal 3 to the signal 4, front contact 118 of relay WNB energizes the lamp NKB¹ over bus wire 120 to illuminate the route locking section NKB. This section will be maintained illuminated by reason of the control of lamp NKB¹ in a similar manner as explained for NKA¹. In other words, the contact 105 of the track relay 9T energizes this indicator lamp NKB¹ through polar contact 106 in a right hand position over wire 120 so long as the track circuit 9 is occupied. Similarly, the relay 9ES representing the directional route stick locking for the route, controls through its contact 121 the energization of the lamp NKB¹ with polar contact 106 in a right hand position the same as the relay 8ES controls the indicator lamp NKA¹.

However, we assumed that a route was established between the signals 3 and 4, which means that the relay NCR is picked up and the lock relay L is dropped away. Therefore, immediately upon the energization of both of the relays 5NR and 6XR, a circuit is closed for the relay 5G from (+), through a circuit including front contact 98 of relay 6XR, wire 97, back contact 96 of relay L, front contact 95 of relay NCR, wire 141, back contact 142 of relay 5XR, front contact 143 of relay 5NR, wire 144, windings of relay 5G, to (-).

The picking up of the contacts of the relay 5G causes the signal 5 to change its indication from stop to clear, and also deenergizes the relay M at open back contact 70 for further holding the lock relay L deenergized, as previously described.

This route may be put to stop in the same manner as described for the other routes, namely, by returning the entrance button 5NB to its normal position.

Emergency switch control.—The individual manual control of track switches in an interlocking plant is desirable under certain emergency conditions which may arise such as the operation of a track switch back and forth when it fails to entirely complete an operating stroke by reason of ice, lumps of coal, or the like. Also, it is sometimes necessary to mechanically set up a route through the track layout for the passage of hand cars and the like, although it is not desired to clear a signal for such a route. It is also sometimes desirable to provide means whereby the operator can manually determine which of two routes shall be superior in a group of optional routes, although the system under normal operation automatically determines this superiority between such optional routes. This will be discussed more in detail in connection with the more complicated track layout shown in Fig. 3, merely the details of the individual manual control being discussed at this point.

This individual manual control is provided in accordance with the present invention so as to be possible so long as the track switch may actually be operated, but when it is under the control of the entrance-exit relays, or is locked by reason of the presence of a train, such individual manual control is prevented.

More specifically, the operation of the lever SML from a central position to a normal operating position energizes both of the relays WNA and WNB, but the operation of lever SML from a central position to a reverse operating position energizes the reverse relay WR. This is accomplished by supplying energy for the upper winding of relay WNA through contact 130 in an upper normal operating position and through back contact 131 of relay WR and at the same time supplying energy through contact 132 in an upper normal operating position to the upper winding of relay WNB and through the back contact 131 of relay WR. Likewise, with contact 130 in a lower reverse operating position, the upper winding of relay WR is energized through back contacts 29 and 133 of relays WNA and WNB respectively.

It will thus be apparent, that if either or both of the relays WNA or WNB are energized by reason of the entrance-exit control, then relay WR cannot be energized by the manual lever SML because of open contacts 29 and/or 133. On the other hand, if the entrance-exit control causes the energization of the relay WR, the lever SML cannot cause the energization of either of the relays WNA or WNB because of the open back contact 131. The converse is also true, namely, the individual manual energization of relays WNA and WNB prevents the entrance-exit control of WR, while the individual manual energization of relay WR prevents the entrance-exit control of WNA and WNB.

The relays WNA and WNB, when manually picked up, cause the normal operation of the switch machine by controlling the relay WZ, as previously described; and similarly, the manual picking up of the relay WR causes the reverse operation of the switch machine through the relay WZ, as previously described. This of course assumes that the track switches TSA and TSB can be safely operated by reason of the energized condition of the lock relay L.

The reason that both of the relays WNA and WNB are picked up by the lever SML, is so that both of the route indicator sections NKA and NKB will be illuminated when the crossover is under individual manual control. So far as the actual control of the operation of the crossover is concerned, it could be accomplished by a single one of these relays, as will be readily apparent.

Operation of a single track switch.—It will be readily appreciated that a single track switch requires only two switch control relays, such as relays WNA and WR, although three relays are required for a crossover for the purpose of the entrance-exit control and indication. In other words, for a single track switch, the relay WNB and its contacts can be readily eliminated. In place of the contact 85 on the relay WNB, the circuits would be carried directly to the relay WR and the other circuits would likewise be modified in accordance with the particular track layout and conditions involved in the remaining portions of the system. Similarly, the contact 132 on the lever SML and its circuit can be eliminated. The back contact 133 will be elimi-

inated with negative potential directly applied to the right hand terminal of the relay WR.

It will be readily apparent that the contacts 47, 118 and 119 will be unnecessary, also that the stick circuits for the entrance and exit relays will be selected on the basis of a single track switch instead of a crossover with the contact 83 omitted. If the switch TSA were a single switch and did not have the opposite end TSB to form a crossover, there would be no signal 5 and its associated controls so that relay 5NR and 5XR will be eliminated and the circuit from front contact 86 of relay WR will be carried directly to the heel of contact 87 of relay 6NR. Further description along this line appears unnecessary, as the usual principles of circuit work may be used in this connection, enough having already been said to furnish a disclosure for the basis of claims insofar as the present invention is involved in this modification of the disclosure.

Modification of Fig. 4.—Fig. 4 illustrates a modification of the entrance-exit control more specifically applied to the signal 3 as indicated by its reference characters, but this arrangement should be considered as applied to each of the entrance-exit buttons. This form shows how the invention may be practiced without the entrance relays NR by using additional contacts on the entrance buttons NB for the various circuit selections involved.

With reference to Fig. 4, it is apparent that the exit button 3XB has the contact 82 associated therewith, and similarly, the entrance button 3NB has the contact 15 associated therewith, the same as in Fig. 1. But an added contact 151 is provided to take the place of contact 20, while a contact 153 is provided to take the place of contact 65.

When the entrance button 3NB is rotated to an operated position, energy is supplied to the control circuit for the associated switch control relays from (+), through contact 151 in an operated position, back contact 152 of exit relay 3XR, to the circuit selections as shown in Fig. 1, or as shown in Fig. 3 causing the operation of the switch control relays jointly with the operation of the exit relay XR at the opposite end of the self-selecting network.

With the entrance button 3NB in an operated position and the proper selections having been made by the switch control relays, then the signal circuit is completed through a contact 153 of the entrance button 3NB in a similar manner as described in Fig. 1 with regard to contact 65 on relay 3NR.

With the entrance button 3NB in an operated position, it is readily apparent that the closure of contact 82 of exit button 3XB cannot energize the relay 3XR because at such time (+) energy is supplied through contact 15 in an operated position and back contact 150 to the stick circuit selection for the exit relay XR at the opposite end of the particular route selected.

Assuming the entrance button 3NB to be in a normal position, the actuation of the exit button 3XB closes a circuit for the relay 3XR from (+), through a circuit including contact 15 in a normal position, back contact 82 of exit button 3XB, windings of relay 3XR, to (—). When the self-selecting network has set up the proper circuit selections for the exit relay stick circuit, such stick circuit for relay 3XR includes front contact 150 in a manner which is entirely analogous to the description with regard to Fig. 1.

This arrangement provides the same interlock

as provided in Fig. 1, that is, the operation of the entrance button 3NB cannot interrupt the control for the exit relay 3XR when it is energized, nor can the operation of the exit button 3XB interrupt or change the control provided by the entrance button 3NB when such button is in an operated position.

Track layout of Fig. 3.—A track layout has been illustrated in Fig. 3 as including a stretch of double track between signals 11—12 and signals 13—14 with two turnout tracks including switches 16TS and 18TS, as well as entering signals 10 and 15. Two crossovers are provided, one including the track switches 17TSA and 17TSB, and the other including the track switches 19TSA and 19TSB.

Associated in the central office with each of the signal locations are the entrance and exit buttons and each of the indicators as described in connection with Fig. 1. In other words, the track layout is provided in miniature on the control panel the same as described for Fig. 1 but arranged for the complicated track layout herein shown. The entrance and exit buttons have not been shown, but the entrance and exit relays NR and XR, which are controlled thereby, have been shown in block form and given reference characters with preceding numerals to designate the particular signal locations with which they are associated. As these entrance and exit relays are connected as typically taught in Fig. 1, it is believed that further details in this connection are unnecessary in view of the detailed description given for such operation and control in connection with Fig. 1.

Each of the crossovers is provided with switch control relays WNA, WR and WNB, shown specifically as relays 17WNA, 17WR and 17WNB for the crossover including track switches 17TSA and 17TSB, and shown as relays 19WNA, 19WR and 19WNB for the crossover including track switches 19TSA and 19TSB. The switch control relays 16WR and 16WN are shown for the track switch 16TS; and the relays 18WN and 18WR are shown for the track switch 18TS.

Each group of switch controlling relays WNA, WR and WNB (or WN and WR) have associated therewith the necessary apparatus for controlling their track switches as typically shown in Figs. 1 and 2. These switch control relays also include contacts for the control of the illuminated track diagram indicators as typically shown in connection with Figs. 1 and 2, all of which has been omitted for the sake of simplicity. Also, each group of switch control relays has associated therewith an emergency switch control lever SML, but only the emergency switch control levers 16SML and 18SML have been shown in detail, as their associated track switches 16TS and 18TS are the only ones in Fig. 3 which have what has been termed as derail protection control provided in connection therewith, while the remaining groups of switch control relays have their emergency switch control levers associated therewith the same as described in connection with Fig. 1.

The switch control relays WNA, WR and WNB (or WN and WR) have contacts for selecting the stick circuits for the exit relays XR as typically taught in Fig. 1.

Fig. 3 has been entirely limited to the features which differ from Figs. 1 and 2, rather than complicating it with all the details which would necessarily be duplicated from Figs. 1 and 2. The arrangement of Fig. 3 is more particularly

directed to the manner in which the entrance-exit control provides for selectively energizing the switch control relays in an interlocking group having a complex track layout. This feature is accomplished in accordance with Fig. 3 by what has been termed a self-selecting route network based upon the series circuit principle that is, when the opposite ends of a route circuit are energized, all of the switch controlling relays in that circuit are energized in series and the picking up of the switch controlling relays in such circuit effectively prevent the picking up of switch controlling relays for setting up conflicting routes.

For example, let us consider that the operator is desirous of clearing a route from the signal 11 to the signal 13. To do this, he operates the entrance button which energizes the entrance relay 11NR, and then actuates the exit button which energizes the exit relay 13XR. This closes an energizing circuit from (+), through a circuit including front contact 160 of relay 11NR, back contact 161 of relay 11XR, back contact 162 of relay 17WR, lower winding of relay 17WNA, back contact 163 of relay 16WR, lower winding of relay 16WN, back contact 164 of relay 19WR, lower winding of relay 19WNA, front contact 165 of relay 13XR, to (-). The current which flows in this circuit causes the relays 17WNA, 16WN and 19WNA to pick up and operate their respective track switches to corresponding normal positions. The picking up of relays 17WNA, 16WN and 19WNA completes a stick circuit for the exit relay 13XR in a manner analogous to the stick circuit for relay 4XR for example. After the track switches are operated into correspondence with their controls, a signal clearing circuit for signal 11 is completed upon the same basic principles as described in connection with Figs. 1 and 2.

With the cleared condition of the route from the signal 11 to the signal 13, a conflicting route cannot be established. For example, if the entrance relay 11NR were picked up to put negative potential on the wire 166, the relay 19WR cannot be picked up because of the open condition of back contact 167 of relay 19WNA. Similarly, the other branch circuit extending from the wire 166 cannot energize the relay 17WR by reason of open back contact 168 of relay 17WNA.

This arrangement of Fig. 3 provides the same features of control and indication as pointed out in connection with Figs. 1 and 2. As above mentioned, a route is wholly dependent upon its governing entrance button NB, so that in this particular example the return of entrance button 11NB (not shown) to a normal position restores the signal 11 to a stop indicating condition.

With a self-selecting network of this character, there are certain route circuits in the interlocked group which do not include as many switch control relays as do others in the same group, so that in such cases it is necessary to provide balancing resistors in the route circuits having the smaller number of switch control relays. For example, the route between the signals 10 and 13 includes only two track switches while the route between the signals 11 and 13 includes three switches. Thus, the route circuit in the self-selecting network corresponding to the route between signals 10 and 13 is compensated by the provision of the resistor 170. To be more specific, and considering the actuation of the entrance relay 13NR and the exit relay 10XR, a route circuit is closed from (+), through a circuit including front contact 171 of relay 10XR, compensating resistor 170, lower winding of relay 75

16WR, back contact 172 of relay 16WN, back contact 164 of relay 19WR, lower winding of relay 19WNA, back contact 165 of relay 13XR, front contact 173 of relay 13NR, to (-). The energy which flows in this circuit of course energizes the relays 16WR and 19WNA in series causing their respective switches to operate to corresponding reverse and normal positions and accomplishes the clearing of the signal 13 in the usual way, as described in connection with Figs. 1 and 2.

Optional routes.—This track layout provides what has been conveniently termed optional routes, that is, two or more routes between two particular points. The system of the present invention is arranged to automatically determine the superiority between such routes, that is, the particular one of the optional (or parallel) routes that shall be selected as the preferred route at any one time.

20 In this particular track layout there is one route between the signals 14 and 11 over the track switches 19TSA and 19TSB in reverse positions, and another route over the track switches 17TSA and 17TSB in reverse positions. The self-selecting network has been arranged so as to give the superiority to the route over the track switches 19TSA and 19TSB in reverse positions when there is no conflicting route.

For example, let us assume that the operator first actuates the entrance button 11NB (not shown) energizing the relay 11NR, and then actuates the exit button 14XR (not shown) energizing the relay 14XR. Two route circuits are thereby momentarily established.

35 The first route circuit is closed from (+), through a circuit including front contact 160 of relay 11NR, back contact 161 of relay 11XR, back contact 162 of relay 17WR, lower winding of relay 17WNA, back contact 163 of relay 16WR, lower winding of relay 16WN, back contact 174 of relay 19WNB, lower winding of relay 19WR, back contact 167 of relay 19WNA, wire 166, front contact 175 of relay 14XR, to (-).

40 The second route circuit is closed from (+), through a circuit including front contact 160 of relay 11NR, back contact 161 of relay 11XR, back contact 176 of relay 17WNB, lower winding of relay 17WR, back contact 168 of relay 17WNA, lower winding of relay 18WN, back contact 177 of relay 18WR, lower winding of relay 19WNB, back contact 178 of relay 19WR, wire 166, front contact 175 of relay 14XR, to (-).

45 Both of these circuits are energized simultaneously, but the relays 17WR, 18WN, and 19WNB are made slow acting, while the relays 17WNA, 16WN and 19WR are relatively quick acting and therefore pick up immediately. As soon as the relay 19WR picks up, which is before the relay 19WNB, for example, the open back contact 178 deenergizes the second route circuit. Therefore, the first route circuit is given the preference or superiority.

50 However, it may happen that a route is set up between the signal 13 and the signal 10 causing the relays 19WNA and 16WR to be energized. Under such circumstances, the back contact 167 of relay 19WNA is opened, so that only the second route circuit is energized. This causes the relays 19WNB, 18WN and 17WR to be picked up. Thus, an automatic selection between optional routes is provided by the system of the present invention.

55 For one reason or another, it might be desirable to select the second route over the track switches 17TSA and 17TSB in reverse positions

even though the track switch 19TSA is not included in an established route. All that is necessary to do this is for the operator to actuate the emergency switch control lever 17SML (not shown) to a reverse position which energizes the relay 17WR. The picked up condition of the relay 17WR opens the back contact 182 in the route circuit for the first route and prevents the superior optional route from being automatically selected, and allows the relays 18WN and 19WNB to be energized in series with the lower winding of the relay 17WR upon the actuation of the entrance and exit relays for the signals 11 and 14.

Derail protection.—When a route is set up over the track switches 17TSA and 17TSB in reverse positions including the track switch 18TS in either a normal or a reverse position, means is provided in accordance with the present invention to give derail protection to this route by operating the track switch 16TS to a reverse position. In other words, when a route is automatically set up between the signals 11 and 15, or when a route is set up between the signals 11 and 14 by reason of the manual operation of the emergency switch lever 17SML (not shown), means is provided which operates the track switch 16TS to its reverse position so that any train which might overrun the signal 13, will be shunted on to the turnout track. This is accomplished by suitable circuit selections closing a circuit for the relay 16WR from (+), through a circuit including the upper windings of relay 16WR, back contact 180 of relay 16WN, front contact 181 of relay 17WR, to (-). Such control of the track switch 16TS by the derail protecting means, does not prevent that track switch from being employed in a route which is not conflicting with the established route. In other words, when a route is set up over the track switches 17TSA and 17TSB in reverse positions, a route may be set up between the signals 10 and 13, or between the signals 10 and 14 with the track switch 18TS in a reverse position.

Similar control is provided for the track switch 18TS by reason of front contact 182 of relay 19WR which is effective to energize the relay 18WR when a route is established over the track switch 19TSA and 19TSB in reverse positions. The track layout of Fig. 3 only has these two possible examples of derail protection, but it is to be understood that any track layout to which the present invention is applied may have this derail protection applied at all possible situations, by merely causing the route to be protected to energize the proper switch control relay for the protecting switch through its individual manual emergency switch control winding. The individual manual control winding for the switch control relays is employed in connection with this feature so that the derail protecting circuits will not become involved in the usual route selections.

Having thus described an electric interlocking system for railroads, as one specific embodiment of the present invention, it is to be understood that various modifications, adaptations, and alterations may be applied to meet the requirements of practice without in any manner departing from the spirit or scope of the invention except as limited by the appended claims.

What I claim is:

1. In a centralized traffic controlling system for railroads, a track layout containing a plurality of routes formed by track switches, cir-

cuit controllers for the ends of said routes, wires connecting said circuit controllers in a manner corresponding to said track layout, whereby there is a continuous route circuit for each route through the track layout, relays included in certain of said wires so that there is a relay in each route circuit corresponding to the trailing point position for each track switch in the route for that route circuit, whereby the closure of a circuit controller at each of the opposite ends of a route circuit energizes a relay for each track switch in the corresponding route which relay is representative of the proper position for that track switch in such route, contacts on each of said relays for opening, when that relay is energized, the route circuits for those routes, which conflict with the route corresponding to said energized route circuit that are possible when the track switch for that relay is in an opposite position, and other means for individually energizing each of said relays.

2. In an interlocking system for railroads, a track layout containing a plurality of routes formed by track switches, circuit controllers for the ends of said routes, wires connecting said circuit controllers in a network symmetrically arranged to correspond with said track layout, whereby there is a continuous route circuit for each route through the track layout, normal and reverse switch control relays for each of said track switches except in the case of a crossover where a single reverse relay is common to both track switches of the crossover, said relays being included in the respective branches of said network corresponding to the trailing positions of the track switches which such relays represent, whereby the closure of a circuit controller at each of the opposite ends of a route circuit energizes the proper normal or reverse relay for each track switch necessary to establish the corresponding route, and back contacts on each of said normal and reverse switch control relays for opening said route circuits in which the opposite reverse or normal switch control relay is included, and manually operable means for individually energizing each of said switch control relays, said means being effective to energize only the normal or the reverse control relay for each switch at any one time.

3. In an interlocking system for railroads, a track layout containing a plurality of routes formed by track switches, circuit controllers for the ends of said routes, wires connecting said circuit controllers in a network symmetrically arranged to correspond with said track layout, whereby there is a continuous route circuit for each route through the track layout, normal and reverse switch control relays for each of said track switches except in the case of a crossover where a single reverse relay is common to both track switches of the crossover, said relays being included in the respective branches of said network corresponding to the trailing positions of the track switches which such relays represent, whereby the closure of a circuit controller at each of the opposite ends of a route circuit energizes the proper normal or reverse relay for each track switch necessary to establish the corresponding route, back contacts on each of said normal and reverse switch control relays for opening said route circuits for those routes which conflict with the route corresponding to said energized route, switch machines for respectively operating said track switches, circuit means associated with each said switch machine and con-

trolled by the respective normal and reverse switch control relays for that track switch for causing its normal and reverse operation, a locking relay for each track switch for preventing the response of its switch machine to its said switch control relays when such locking relay is deenergized, a pick up circuit for each locking relay including back contacts of its said normal and reverse switch control relays, and a stick circuit for each said locking relays including a front contact of such locking relay and contacts which complete such stick circuit only while said normal and reverse switch control relays for the corresponding track switch are out of correspondence with such track switch.

4. In an interlocking system for railroads, a track layout containing a plurality of routes formed by track switches, a stay-where-put entrance button for the entrance end of each router, a self-restoring exit button for the exit end of each route, an exit relay for each exit button having a pick up circuit controlled by such exit button, a circuit network symmetrically arranged to correspond with said track layout, whereby there is a continuous route circuit for each route through the track layout, normal and reverse switch control relays for each of said track switches except in the case of a crossover where a single reverse relay is common to both track switches of the crossover, said relays being included in the respective branches of said network corresponding to the trailing positions of the track switches which such relays represent, entrance contacts on each of said entrance buttons and exit contacts on each of said exit relays, means effective upon the actuation of only an entrance button at one end of a route and the exit button at the opposite end of that route to close an entrance contact and an exit contact for energizing the corresponding route circuit so that the proper normal or reverse relay for each track switch is picked up to establish the corresponding route, front contacts on said normal and reverse switch control relays for completing a circuit corresponding to said route, which circuit is wholly dependent for energization upon the said entrance button for that route and which circuit maintains energized the exit relay for such route, and back contacts on each of said normal and reverse switch control relays for opening the circuit branches for the switch control relay requiring the opposite position of the track switch, whereby conflicting route circuits cannot be energized.

5. In an interlocking system for railroads, a plurality of railway tracks interconnected by switches to form a plurality of routes, normal and reverse control relays for each of said switches, a plurality of interconnected route circuits for said plurality of routes each of said route circuits including in series the normal or the reverse control relay for each switch in the corresponding route, route control means including manually controlled means and a source of current for energizing a route circuit and the control relays included therein, means controlled by the normal and the reverse control relays for each switch for operating the corresponding switch to normal and reverse positions respectively, and other manually controlled means for individually energizing either the normal or the reverse control relay for each track switch only if the opposite normal or reverse control relay is deenergized, whereby the route control and the individual control is effectively interlocked.

6. In an interlocking system for railroads, a plurality of railway tracks interconnected by switches to form a plurality of routes, a normal and a reverse control relay for each of said switches, a manually operable contactor means for each route end, an exit relay for each route end, a plurality of route circuits one for each of said routes and each of which includes in series the normal or the reverse control relay for each switch in the corresponding route and also a contact controlled by the manually operable contactor means for the entrance end of the route as well as a front contact of the exit relay for the exit end of the route for the direction of traffic movement with which the circuit is then associated and also a source of current for operating the control relays in the circuit, means controlled by the normal and the reverse control relays for each switch for operating the corresponding switch to normal and reverse positions respectively, a pick up circuit for each exit relay controlled by said manually operable contactor means for the corresponding route end, and a stick circuit for each exit relay separate from said route circuits and selectively made up by said normal and reverse control relays of the then energized route circuit and dependent upon the manually operable contactor means for the entrance end of the corresponding route for the direction of traffic with which the route circuit is then associated.

7. In an interlocking system for railroads, a plurality of railway tracks interconnected by switches to form a plurality of routes, a normal and a reverse control relay for each of said switches, a manually operable contact means for each route end, an exit relay for each route end, a plurality of route circuits one for each of said routes and each of which includes in series the normal or the reverse control relay for each switch in the corresponding route and also a contact controlled by the manually operable contact means for the entrance end of the route as well as a front contact of the exit relay for the exit end of the route for the direction of traffic movement with which the circuit is then associated and also a source of current for operating the relays of the circuit, means controlled by the normal and the reverse control relays for each switch for operating the corresponding switch to normal and reverse positions respectively, a pick up circuit for each exit relay controlled by said manually operable contact means for the corresponding route end, a stick circuit for each exit relay separate from said route circuits and selectively made up by front contacts of said normal and reverse control relays of the then energized route circuit and dependent upon the manually operable contact means for the entrance end of the corresponding route for the direction of traffic with which the route circuit is then associated, whereby an exit relay is not stuck up until after the response of all the normal and reverse control relays for the switches in the particular route to be set up, a signal for each route end, and means controlled by said exit relays and said manually operable contact means for the route ends for operating said signals.

8. In an interlocking system for railroads, a plurality of railway tracks interconnected by switches to form a plurality of routes, a stay-where-put entrance button for each route end, a self-restoring exit button for each route end, an entrance relay for each route end, an exit relay

for each route end, a control circuit for each entrance relay energized with the entrance button for its route end in an operated position and including a back contact of the exit relay for that route end, a pick up circuit for each exit relay energized with the exit button for its route end in an operated position and including a back contact of the entrance relay for that route end, normal and reverse switch control relays for each of said switches, a self-selecting circuit network including said normal and reverse control relays rendered effective to energize the proper normal and/or reverse control relays to establish a particular route when only the entrance relay for one end of that route and the exit relay for the opposite end of that route are both picked up, and a stick circuit for each of said exit relays selected by front contacts of the appropriate switch control relays to include a front contact of the entrance relay of the particular route with which that exit relay is then associated.

9. In an interlocking system for railroads, a plurality of railway tracks interconnected by switches to form a plurality of routes, a stay-where-put entrance button for each route end, a self-restoring exit button for each route end, an entrance relay for each route end, an exit relay for each route end, a control circuit for each entrance relay energized with the entrance button for its route end in an operated position and including a back contact of the exit relay for that route end, a pick up circuit for each exit relay energized with the exit button for its route end in an operated position and including a back contact of the entrance relay for that route end, normal and reverse switch control relays for each of said switches, a self-selecting circuit network including a plurality of interconnected route circuits for said plurality of routes each of said circuits including the control winding of either a normal or the reverse control relay for each track switch in the corresponding route and also a back contact of the opposite control relay for each track switch in a corresponding route, means including said entrance and exit relays for energizing each particular route circuit of said self-selecting network in response to the operation of only the entrance button for the entrance point to the particular corresponding route and the exit button for the exit point to the corresponding particular route, means controlled by said normal and reverse relays for each switch for operating the corresponding switch to normal and reverse positions respectively, and a stick circuit for each of said exit relays selected by front contacts of the appropriate switch control relays to include a front contact of the entrance relay of the particular route with which that exit relay is then associated.

10. In an interlocking system for railroads, a plurality of railway tracks interconnected by switches to form a plurality of routes, manually operable contact means for each route end, an entrance relay for each route end, an exit relay for each route end, a circuit for each entrance relay controlled by said manually operable contact means for its route end and including a back contact of the exit relay for that route end, a pick up circuit for each exit relay controlled by said manually operable contact means for its route end and including a back contact of the entrance relay for that route end, normal and reverse switch control relays for each of said

switches for controlling that switch to its normal and reverse positions respectively, a self-selecting circuit network including said normal and reverse control relays rendered effective to automatically energize the proper normal or reverse control relay for each track switch in a particular route to establish that route when the entrance relay for one end of that route and the exit relay for the opposite end of that route are both picked up, and a stick circuit for each of said exit relays separate from said self-selecting network and selectively made up by the control relays of the route with which that exit relay is then associated so as to include a front contact of the entrance relay for that route, whereby said control relays for that route and said exit relay for that route are all dependent for continued energization of the entrance relay for that route.

20 11. In an interlocking system for railroads, a plurality of railway tracks interconnected by switches to form a plurality of routes, manually operable contact means for each route end, an entrance relay for each route end, an exit relay for each route end, a circuit for each entrance relay controlled by said manually operable contact means for its route end and including a back contact of the exit relay for that route end, a pick up circuit for each exit relay controlled by said manually operable contact means for its route end and including a back contact of the entrance relay for that route end, normal and reverse switch control relays for each of said switches for controlling that switch to its normal and reverse positions respectively, a self-selecting circuit network including said normal and reverse control relays rendered effective to automatically energize the proper normal or reverse control relay for each track switch in a particular route to establish that route when only the entrance relay for one end of that route and the exit relay for the opposite end of that route are both picked up, a stick circuit for each of said exit relays selected by front contacts of the appropriate switch control relays to include a front contact of the entrance relay of the particular route with which that exit relay is then associated, a signal at each route end for governing the entrance of traffic into the routes emanating from that point, and means controlled by said entrance and exit relays for operating said signals.

12. In an interlocking system for railroads, a plurality of railway tracks interconnected by switches to form a plurality of routes, manually operable contact means for each route end, an entrance relay for each route end, an exit relay for each route end, a circuit for each entrance relay controlled by said manually operable contact means for its route end and including a back contact of the exit relay for that route end, a pick up circuit for each exit relay controlled by said manually operable contact means for its route end and including a back contact of the entrance relay for that route end, normal and reverse switch control relays for each of said switches for controlling that switch to its normal and reverse positions respectively, a self-selecting circuit network including said normal and reverse control relays rendered effective to automatically energize the proper normal or reverse control relay for each track switch in a particular route to establish that route when the entrance relay for one end of that route and the exit relay for the opposite end of that route are

both picked up, a normal and a reverse correspondence relay for each switch respectively picked up only when said normal and reverse control relays for that switch are energized in correspondence with such switch, a lock relay for each switch for preventing operation of that switch when deenergized, an energizing circuit for each lock relay including traffic controlled contacts, back contacts of said normal and reverse correspondence relays for its switch, and back contacts of said normal and reverse control relays for its switch, with a front contact on such lock relay for shunting out said back contacts on said control relays when such lock relay is picked up, whereby each of said track switches is locked as soon as it assumes a proper position for the route in which it is then included as indicated by the energization of its correspondence relays.

13. In an interlocking system for railroads, a plurality of railway tracks interconnected by switches to form a plurality of routes, manually operable contact means for each route end, an entrance relay for each route end, an exit relay for each route end, a circuit for each entrance relay controlled by said manually operable contact means for its route end and including a back contact of the exit relay for that route end, a pick up circuit for each exit relay controlled by said manually operable contact means for its route end and including a back contact of the entrance relay for that route end, normal and reverse switch control relays for each of said switches for controlling that switch to its normal and reverse positions respectively, a self-selecting circuit network including said normal and reverse control relays rendered effective to automatically energize the proper normal or reverse control relay for each track switch in a particular route to establish that route when the entrance relay for one end of that route and the exit relay for the opposite end of that route are both picked up, a normal and a reverse correspondence relay for each switch respectively picked up only when said normal and reverse control relays for that switch are energized in correspondence with such switch, a lock relay for each switch for preventing operation of that switch when deenergized, an energizing circuit for each lock relay including traffic controlled contacts, back contacts of said normal and reverse correspondence relays for its switch, back contact of said normal and reverse control relays for its switch, with a front contact on such lock relay for shunting out said back contacts on said control relays when such lock relay is picked up, whereby each of said track switches is locked as soon as it assumes a proper position for the route in which it is then included as indicated by the energization of its correspondence relays, a signal at each route end, control circuits for each signal including a front contact of said entrance relay at that end, a back contact of each lock relay of the several switches in the then established route, and a front contact of the exit relay for that route.

14. In a centralized traffic controlling system for railroads; a power operated track switch; a signal for governing traffic over said track switch; a traffic condition relay controlled by traffic conditions adjacent said track switch; switch relay means for controlling the normal and reverse operation of said track switch when selectively energized and rendered effective; normal and reverse correspondence relays; a normal

75 circuit for energizing said normal correspondence relay only when said switch relay means is selectively energized to cause a normal operation of said track switch and said track switch is in correspondence therewith; a reverse circuit for energizing said reverse correspondence relay only when said switch relay means is selectively energized to cause a reverse operation of said track switch and said track switch is in correspondence therewith; signal control circuit means for at times clearing said signal when rendered effective, said signal circuit means being selected by front contacts of said correspondence relays; a lock relay for rendering said switch relay means effective when picked up and for rendering said signal circuit means effective when dropped away; a pick-up circuit for said lock relay including back contacts of said switch relay means and a front contact of said traffic relay; and stick circuit means for said lock relay including back contacts of said correspondence relays and a front contact of said traffic relay.

15. In an interlocking system for railroads; a plurality of railway tracks interconnected by power operated track switches to form a plurality of routes; normal and reverse control relays for each of said switches; manually operable contact means for the ends of said routes; a route establishing circuit network having route circuits corresponding to said routes and each route circuit energizing those of said normal and reverse control relays required to be energized to set up the corresponding route, said circuit network including contacts of said control relays in a manner effective to isolate each energized route circuit from all conflicting route circuits, and each particular route circuit of said circuit network being energized in response to the operation of said 20 manually operable contact means for the opposite ends of the corresponding route; and circuit means controlled by certain of said normal and reverse control relays, when such relays are energized by a route circuit, for energizing a particular normal or reverse control relay for a particular conflicting route so as to operate the corresponding track switch to a position to give derail protection to the established route.

16. In an interlocking system for railroads; a plurality of railway tracks interconnected by switches to form a plurality of routes; normal and reverse control relays for each of said switches; manually operable contact means for the ends of said routes; a route establishing circuit network having route circuits corresponding to said routes and each route circuit energizing those of said normal and reverse control relays required to be energized to set up the corresponding route, said circuit network including contacts of said control relays in a manner effective to isolate each energized route circuit from all conflicting route circuits, and each particular route circuit of said circuit network being energized in response to the operation of said manually operable contact means for the opposite ends of the corresponding route; normal and reverse indicator lamps for each of said track switches; and circuit means for energizing each of said indicator lamps whenever the corresponding normal or reverse control relay for that switch is energized independently of the position of the switch.

70 17. In an interlocking system for railroads; a plurality of railway tracks interconnected by switches to form a plurality of routes; a miniature track diagram forming a replica of said track

layout; manually operable control means for the ends of said routes; normal and reverse control relays for each of said track switches; a route establishing circuit network having route circuits corresponding to said routes, each route circuit being capable, when energized, of energizing those of said normal and reverse control relays required to be energized to set up the corresponding route, said circuit network including contacts of said control relays in a manner effective to isolate each energized route circuit from all conflicting route circuits, and each particular route circuit of said circuit network being energized in response to the joint operation of said manually operable contact means for the opposite ends of the corresponding route; means including indicator lamps for each position of each track switch for illuminating linear portions of said track diagram so as to indicate the route set up when illuminated; and circuit means for each indicator lamp controlled by its corresponding normal or reverse control relay so as to be illuminated whenever such control relay is picked up and independently of the position of the corresponding switch.

18. In an interlocking system for railroads; a plurality of railway tracks interconnected by switches to form a plurality of routes; a miniature track diagram forming a replica of said track layout; manually operable control means for the ends of said routes; normal and reverse control relays for each of said track switches; a route establishing circuit network having route circuits corresponding to said routes, each said route circuit being capable, when energized, of energizing those of said normal and reverse control relays required to be energized to set up the corresponding route, said circuit network including contacts of said control relays in a manner effective to isolate each energized route circuit from all conflicting route circuits, and each particular route circuit of said circuit network being energized in response to the joint operation of said manually operable contact means for the opposite ends of the corresponding route; indicator lamps for each position of each track switch so located on said track diagram as to indicate the route set up when illuminated; circuit means for each indicator lamp controlled by its corresponding normal or reverse control relay so as to be illuminated whenever such control relay is picked up; and other circuit means for each of said indicators for maintaining such indicators illuminated whenever a train is occupying the route in which such track switches have been included.

19. In a switch and signal control system, a plurality of track portions interconnected by track switches to form a plurality of routes through a track layout between signal locations, a circuit network including circuit portions corresponding to said track portions and connected to conform to the routes through said track layout, normal and reverse control relays for each of said track switches for governing the normal and reverse operation of the corresponding track switches; manually operable control means for each of said signal locations, means including said circuit network effective in response to the operation of the manually operable control means for an entrance point and the operation of the manually controlled means for an exit point to energize those of said normal and reverse control relays required to set up a route between said entrance and exit points, contacts of said normal and reverse control relays included in said circuit

network and effective when the control relays for the track switches of a particular route are energized to set up that route to isolate the circuit portions of said network corresponding to that particular route from the circuit portions of other routes, circuit means controlled by certain ones of said normal and reverse control relays of said particular normal or reverse route for energizing particular control relays for switches in routes conflicting with said particular route so as to operate the track switches corresponding to said particular control relays to positions to give diverging route protection for said particular route which is then set up, and circuit means for clearing a signal at the entrance end of said particular route dependent upon the continued energization of said circuit portions corresponding to said particular route.

20. In a switch control system for railroads, a plurality of railway tracks interconnected by power-operated track switches to form a plurality of routes, normal and reverse control relays for each of said switches, manually operable contact means for the ends of said routes, route establishing circuit means effective in response to the joint operation of the manually operable contact means for the opposite ends of a particular route to energize the normal or reverse control relays for the track switches in that particular route so as to set up the corresponding route, and circuit means controlled by certain of said normal and reverse control relays, when energized for said particular route, for energizing control relays for certain track switches in routes conflicting with said particular route so as to operate such track switches to positions opposite to the positions required to set up such conflicting routes to thereby prevent trains from travelling over such conflicting routes into track switches included in said particular route.

21. In a switch control system for railroads; a plurality of railway tracks interconnected by power-operated track switches to form a plurality of routes; normal and reverse control relays for each of said switches; manually operable contact means for the ends of said routes; route establishing circuit means effective in response to the joint operation of the manually operable contact means for the opposite ends of a particular route to energize the normal or reverse control relays for the track switches in that particular route so as to set up the corresponding route; circuit means controlled by certain of said normal and reverse control relays, when energized for said particular route, for energizing control relays for certain track switches in routes conflicting with said particular route so as to operate such track switches to positions opposite to the positions required to set up such conflicting routes to thereby prevent trains from travelling over such conflicting routes into track switches included in said particular route; a normally inactive auxiliary lever for each of said track switches, said levers having normal and reverse operated positions; and circuit means associated with each lever for energizing its normal or reverse control relay when such lever is actuated to a corresponding normal or reverse position only provided the opposite normal or reverse control is deenergized, whereby the operation of an auxiliary lever for a track switch cannot interrupt or change the normal or reverse relay in a route set up by said route establishing means.

22. In a switch and signal control system for

railroads; a power-operated track switch including in a detector track section; a signal for governing traffic over said track switch; a normally energized track relay deenergized whenever said detector track section is occupied by a train; a lock relay; switch control relay means for controlling the normal and reverse operation of said track switch; when said lock relay is picked up, in accordance with the selective energization of such switch control relay means; a normal circuit for energizing said normal correspondence relay only when said switch control relay means is selectively energized to cause the normal operation of said track switch and said track switch is in correspondence therewith; a reverse circuit for energizing said reverse correspondence relay only when said switch control relay means is selectively energized to cause a reverse operation of said track switch and said track switch is in correspondence therewith; a pick-up circuit for said lock relay including back contacts of said switch control relay means, a front contact of said track relay, and back contacts of said normal and reverse correspondence relays; stick circuit for said lock relay including a front contact of said lock relay, said back contacts of said normal and reverse correspondence relays, and said front contact of said track relay, whereby the back contacts of said switch control relay means are excluded from the control of said lock relay when it is once picked up; and a circuit for clearing said signal, said circuit being closed only when a particular one of said correspondence relays is picked up and said lock relay is dropped away.

23. In an interlocking system for railroads; a plurality of railway tracks interconnected by power-operated track switches to form a plurality of routes, and said tracks being divided into track circuits; a miniature track diagram forming a replica of said track layout; a manually operable contact means on said track diagram for the ends of said routes; normal and reverse control relays for each of said track switches for controlling its power operation; route establishing circuit means effective in response to the joint operation of the manually operable contact means for only the opposite ends of a particular route to energize the normal or reverse control relays for the track switches in that particular route so as to operate the track switches to positions to set up such particular route; normal and reverse indicator lamps for each position of each track switch so located on said track diagram as to indicate the position of each switch by the illumination of the corresponding normal or reverse indicator lamps; circuit means for each indicator lamp controlled by its corresponding normal or reverse control relay so as to be illuminated when such control relay is picked up; and other circuit means for each indicator lamp controlled so as to be illuminated in accordance with the position of its track switch whenever the track circuit in which its track switch is located is occupied by a train; whereby a route is visually indicated on said track diagram whenever it is set up or is occupied by a train.

24. In combination, a detector section of railway track including a two-position track switch, 70 a track relay for said detector section, indication means controlled in accordance with the position and locked condition of the track switch, a track diagram arranged to form a miniature representation of said detector section, three lamps for

illuminating the tracks of said diagram comprising one for each branch track extending in the trailing direction from the switch and one for the single track extending in the facing direction from the switch, a circuit controlled only by a back contact of said track relay for lighting said single track lamp, and a circuit controlled by a back contact of said track relay and by said indication means for lighting one branch track lamp or the other in accordance with the position of the track switch.

25. In combination, a detector section of railway track including a two-position track switch, a track relay for said detector section, indication means controlled in accordance with the position and locked condition of the track switch, a track diagram arranged to form a miniature representation of said detector section, a lamp for illuminating each branch track of said diagram extending in a trailing direction from the representation of the track switch, and a circuit controlled by a back contact of said track relay and by said indication means for lighting one branch track lamp or the other in accordance with the position of the track switch.

26. In an interlocking system for railroads, a track layout comprising a plurality of railroad tracks connected by power-operated track switches to form a plurality of routes between signal locations, a control panel having thereon a miniature track diagram of said track layout, manually operable contact means located on said track diagram adjacent each signal location, a stick relay for each route end, a pick-up circuit for each stick relay controlled by the manually operable contact means for the corresponding route end, normal and reverse switch control relays for governing the operation of the switches to the corresponding normal or reverse position, 40 a route establishing circuit network comprising a plurality of interconnected route circuits each corresponding to one of said routes and responding to the operation of said manually operable contact means belonging to the signal locations, 45 for the ends of a given route to energize the route circuit of the network for that particular route, each of said route circuits including in series the normal or reverse switch control relay for the corresponding route and a front contact of the stick relay for the exit end of that route, and stick circuit means including contacts of said switch control relays for maintaining the stick relay at the exit end of a given route energized until the corresponding route circuit is de-energized.

27. In a switch and signal control system for railroad track layouts having a plurality of tracks connected by power-operated track switches movable to provide a plurality of routes between signal locations, the combination with a miniature track diagram of said track layout, a manually operable device located on said track diagram adjacent each signal represented thereon and adapted to be actuated by an operator to define the corresponding signal location as the entrance or exit end of a desired route, route establishing means responsive to the joint actuation of the manually operable devices for the signal locations at the ends of any given route for positioning the track switches in that route to the normal or reverse position as required and for controlling the clearing of a signal for governing train movement through that route, a detector track section and a track relay for each switch, a plurality of directional stick re-

lays associated with each of said detector track sections and controlled by their track relays, means effective when a route is set up by said route establishing means for operating one of said stick relays for each of the detector track sections in that route, and visual indicating means on said track diagram for illuminating substantially linear portions of track on said track diagram belonging to the normal and reverse positions of each of said switches when a directional stick relay for the corresponding detector track section is in its operated condition, whereby the illumination of portions of the track diagram to define the position of the switches in an established route is maintained while a train is travelling through that route.

28. In an interlocking system, a track layout comprising, a plurality of track sections interconnected by different switches to form different traffic routes between signal locations, said track layout including two alternative routes between the same signal locations one of which is preferred and the other of which is secondary, a miniature track diagram of the track layout having a manually operable contact for each route end, a normal and a reverse switch control relay for each switch governing the operation thereof to the normal or reverse position, a route network comprising, a plurality of interconnected route circuits each corresponding to one of said routes and each including in series the normal or the reverse switch control relay for each switch in the corresponding route, means responsive to the joint operation of the contacts for the opposite ends of a given route to energize the route circuit to pick up the switch control relays for that route, said means being normally effective in the case of said alternative routes to energize the route circuit to pick up the switch control relays for one preferred route only, said means being effective in case such preferred route is not available to cause energization of the route circuit to pick up the switch control relays for the secondary route only, and means controlled by each route circuit when energized to operate one or more of the track switches as required to establish the corresponding route and also to control the clearing of a signal for train movement over that route.

29. In an interlocking system; a track layout comprising a plurality of track sections interconnected by track switches to form different traffic routes between signal locations, said track layout including at least two alternative routes between two of the signal locations, one of which alternative routes is preferred and the other of which is secondary; a control panel having a miniature track diagram of the track layout; manually operable contact means on said track diagram for each route end; a normal and a reverse switch control relay for each track switch except in the case of a crossover where a single reverse switch control relay is common to both of the track switches of the crossover; a route establishing circuit network comprising a plurality of interconnected route circuits each route circuit corresponding to one of said routes, and each including in series the normal or the reverse switch control relay for each switch in the corresponding route; means responsive to the joint operation of the manually operable contact means for the opposite ends of a given route to energize the route circuit for that route to pick up the normal and reverse switch control relays in such route circuit, said means being nor-

mally effective in the case of said alternative routes to energize the route circuits for both such routes but to pick up the switch control relays for the preferred route more quickly than the switch control relays for the secondary route can respond; contacts on said normal and reverse switch control relays included in said route establishing circuit network and effective when the switch control relays for the track switches of a particular route are picked up to separate the circuit portions of said network corresponding to that particular route from all other route circuits and also prevent the energization of the route circuits for conflicting routes; and circuit means controlled by the switch control relays for each track switch to operate that track switch to the normal or reverse position when the normal or reverse switch control relay is picked up, whereby the operation of manually operable contact means for the opposite ends of a particular route causes the establishment of that route and in the case of alternative routes causes the establishment of a predetermined one of such routes.

30. In a switch and signal control system; a plurality of track portions interconnected by track switches to form a plurality of routes between signal locations of a track layout, said track layout including at least two alternative routes between two of said signal locations; a route establishing circuit network including circuit portions corresponding to said track portions and connected to conform to the routes through said track layout; a normal and a reverse switch control relay for each of said track switches except in the case of a crossover where a single reverse switch control relay is common to the track switches for both ends of the crossover, said normal and reverse switch control relays for each switch being included in series in the route establishing circuit network in positions corresponding to trailing point positions for its corresponding track switch, and in the case of alternative routes between two signal locations each normal and reverse switch control relay for a preferred one of such routes being slow acting upon its energization; contacts on said normal and reverse switch control relays included in said route establishing circuit network in such a manner as to be effective, when the switch control relays for the track switches of a particular route are energized, to separate the circuit portions of said network corresponding to that particular route from all other circuit portions of said route establishing network, manually operable contact means for each signal location and effective upon its actuation to always apply a particular electrical potential to the circuit portion of said route establishing network terminating for such signal location, said particular potentials being of opposite polarity for the opposite ends of said routes, whereby the actuation of a manually operable contact means for the entrance and exit ends of particular route energizes the normal and reverse switch control relays for all of the track switches in that route as required with such energization always having current flow in the same direction irrespective of the direction of traffic to be established in the corresponding route, and whereby the normal and reverse control relays for a preferred route are effectively energized before the control relays of a secondary route and effect the opening of the circuit portions for such secondary route; and circuit means controlled by

the switch control relays for each track switch to operate that track switch to the normal or reverse position corresponding to the particular normal or reverse control relay picked up.

31. In a system for controlling power operated track switches, a track layout including a plurality of track switches to form a plurality of routes between opposite ends of the layout there being at least two alternatives for use between two of the opposite route ends, manually operable circuit controllers for the ends of said routes, wires connecting said circuit controllers in a manner to form a circuit network corresponding to said track layout, switch control relays included in certain of said wires so that there is a switch control relay for each trailing position of each track switch in every available route through the track layout, means effective upon the operation of said manually operable circuit controllers for route ends at the opposite ends of the track layout for applying opposite potentials to the wires extending to such circuit controllers to thereby energize the normal and reverse switch control relays for the switches of the route or routes between such route ends, a contact on each switch control relay for opening the circuit of the switch control relay for the opposite position of its track switch, means for rendering certain of said switch control relays slow in picking up so as to give a preference to a predetermined one of the route circuits for the alternative routes but allowing the switch control relays of the route circuit for the other route to become picked up if the preferred route is unavailable, an auxiliary winding on each of said switch control relays, and auxiliary circuit means for at times individually energizing said auxiliary windings of certain of said switch control relays.

32. In a switch control system for railroads; a track layout including a plurality of track switches to form a plurality of routes through the track layout, normal and reverse switch control relays for each of said track switches except in the case of a crossover where a single reverse switch control relay is common to the track switches for both ends of the crossover, circuit means controlled by the normal and reverse switch control relays for each switch for governing the power operation of that switch to the corresponding normal or reverse position in accordance with the particular switch control relay then energized, manually operable contact means for the ends of said routes, route establishing means effective in response to the joint operation of the manually operable contact means for the opposite ends of a particular route to energize the normal or reverse switch control relays for the track switches as required to set up that particular route, an auxiliary winding on each of said normal and reverse switch control relays, a normally inactive auxiliary switch control lever for each of said track switches and each of said levers having normal and reverse operated positions, and circuit means controlled by each lever for energizing its associated normal or reverse switch control relay when such lever is actuated to a corresponding normal or reverse operated position only provided the opposite normal or reverse switch control relay is deenergized, said means acting in the case of a crossover to energize the normal switch control relays for both of the track switches at the opposite end of such crossover, whereby the operation of an auxiliary switch control lever for a track switch cannot interrupt or change the normal or reverse con-

trol relay in a route set up by said route establishing means.

33. In an interlocking control system, a track layout comprising a plurality of track sections interconnected by track switches to form different traffic routes, a track relay for each section, a miniature track diagram of said track layout having linear portions representing the track sections, route control means for each route effective when energized to operate the track switches as required to establish such route, a directional stick relay for each direction for each track section, means effective when a route is fully established for releasing selected ones of said relays for one direction including one relay for each section of such route, an indication circuit means for each section controlled by back contacts of the two directional relays for such section, means controlled by said indication circuit means for illuminating the corresponding section of the representation of the established route in the track diagram when either one of said associated directional stick relays is deenergized, and means responsive to the movement of a train over such route to reenergize the stick relays for the route.

34. In a switch and signal control system for track layouts comprising a plurality of track sections connected by one or more track switches to form different traffic routes, a miniature track diagram of said track layout including linear portions adjacent the switches representing their normal and reverse positions, visual indicating means including lamps for illuminating said linear portions substantially throughout their length, switch control relays for governing the operation of the switches to normal and reverse positions, circuits controlled by said switch control relays for lighting said lamps, manually operable buttons on said track diagram for designating entrance and exit ends of desired routes, route control means responsive to the actuation of buttons to designate the entrance and exit ends of a route for energizing the appropriate switch control relays to cause operation of track switches to positions required for said route, switch position indicating contacts closed in accordance with the operated position of said switches, a section locking relay for each track section automatically de-energized when that track section is included in an established route and maintained de-energized until a train has been passed over said track section, and circuit means controlled by back contacts of said section locking relays and by said switch position indicating contacts for selectively lighting said lamps to illuminate linear portions of said track diagram included in an established route although said switch control relays are de-energized.

35. In an interlocking control system, a track layout comprising a plurality of track sections containing track switches adapted to be interconnected to form different traffic routes, a track relay for each section, a miniature track diagram of said track layout having linear portions representing the track sections, manually operable buttons on said track diagram for designated entrance and exit ends of desired routes, route control means for each route effective when energized by actuation of buttons to designate entrance and exit ends of that route to operate the track switches as required to establish such route, a section locking relay for each direction for each track section, each effective when de-energized to prevent the operation of the track switch in such section, means effective when a

route is established for releasing selected ones of said relays for one direction including one for each section of said route, indicator means for illuminating each of said linear portions substantially throughout its length, circuit means effective to control the indicator means for any section when one section locking relay or the other for such section is deenergized for illuminating the corresponding portion of the representation of the established route on the track diagram ahead of a train, electric lamps associated with each indicator means and adapted when lighted to indicate that the corresponding track section is occupied by a train, circuit means effective when the track relay of a track section is deenergized for lighting said corresponding lamp, and means responsive to the movement of a train over such section of a route to reenergize the locking relay for such section.

36. In a switch and signal control system of the entrance-exit type, a track layout including a plurality of track switches operable to different positions to set up different routes through the track layout, normal and reverse switch control relays for each switch acting when respectively energized to operate that switch to a corresponding normal or reverse position, manually operable buttons for the entrance and exit ends of the routes afforded by the track layout, route establishing means responsive to the operation of buttons to designate the entrance and exit ends of a route to energize the normal or reverse switch control relay as required for the appropriate switches to set up that route, the energization of a switch control relay to operate a switch to either position rendering said route establishing means ineffective with respect to all routes over that switch in the other position, and auxiliary manually operable switch control means for each switch operable from an inactive condition to cause energization of either the normal or the reverse switch control relay for the corresponding switch only if the switch control relay for the other position has not been energized by said route establishing means, whereby control of a switch by its auxiliary control means renders said route establishing means ineffective to respond to the operation of buttons for the ends of routes in conflict with such controlled position of said switch.

37. In a switch and signal control system for railroads, a track layout including a plurality of track switches operable to different positions to set up different traffic routes through the track layout, manually operable control buttons for the entrance and exit ends of the routes, normal and reverse switch control relays for each of said track switches, each control relay acting when energized to cause the operation of its track switch to a corresponding normal or reverse position, route establishing circuit means responsive to the operation of the control buttons to designate the entrance and exit ends of any given route for effecting the energization of those switch control relays required to establish that given route, said route establishing circuit means including back contacts of said normal and reverse switch control relays so that the energization of the switch control relays for any given route opens the energizing circuits of the switch control relays involved in all conflicting routes, an auxiliary switch control lever for each of said track switches having an inactive position together with normal and reverse control positions, and circuit means associated with each auxiliary switch control lever rendered active

to energize the associated normal or reverse switch control relay when the auxiliary lever is operated to the corresponding normal or reverse position, said circuit means for the normal switch control relay including a back contact of the associated reverse switch control relay and said circuit means for said reverse switch control relay including a back contact of said normal switch control relay, whereby said route establishing means and said auxiliary switch control lever are interlocked with respect to each switch so that said auxiliary lever is effective only if said route establishing means is inactive and said route establishing means is effective only if said auxiliary lever is inactive.

38. In a system of the entrance-exit type, a track layout comprising a plurality of track sections interconnected by track switches to form different traffic routes, a control panel having thereon a miniature track diagram of said track layout having translucent linear portions of the represented track, manually operable control buttons on said control panel operable to designate the entrance and exit ends of the different routes afforded by the track layout, switch control means for governing the power operation of each of the track switches to normal or reverse positions, route establishing circuit means responsive to the manual actuation of the control buttons to designate the entrance and exit ends of any given route for controlling the switch control means of the switches in that route to cause the operation of such switches to the normal or reverse positions required to establish that route, said energization of such switch control means also acting to render ineffective the route establishing means with respect to all routes conflicting with said given route, means associated with each switch control means and controlled thereby to illuminate a linear portion of the represented track on said track diagram to identify the normal or reverse position of the track switch in accordance with the then energized condition of such switch control means, and an auxiliary switch control lever associated with each switch and operable from a neutral position to normal or reverse controlling positions for energizing the associated switch control means to effect the normal or reverse operation of the corresponding track switch, and at the same time rendering ineffective said route establishing circuit means for routes in conflict with the position of the switch thus determined by the auxiliary switch control lever, and also effecting the illumination of the linear portions on said track diagram representing the normal or reverse position of the corresponding switch.

39. In a switch and signal control system of the entrance-exit type, a track layout including a plurality of track switches operable to different positions to provide different traffic routes over the track layout, a control panel having thereon a miniature track diagram provided with translucent linear portions of the represented track adjacent the switches to constitute when illuminated normal and reverse visual indicators of switch position, electrically interlocked normal and reverse switch control relays for each switch acting when energized to operate that switch to the corresponding normal or reverse position, manually operable entrance and exit buttons located on said track diagram at points corresponding with entrance and exit signal locations, route establishing means responsive to the operation of the entrance and exit buttons for a

route to energize the normal or reverse switch control relays for all of the switches included in that route as required to set up that route, said route establishing means comprising circuit means belonging to each route and controlled by back contacts of the normal or reverse switch control relays for setting up conflicting routes, so that the energization of switch control relays to establish any given route renders ineffective the route establishing means with respect to all routes conflicting with that given route, an auxiliary switch control lever for each switch operable from an inactive position to a normal or reverse controlling position to cause energization of the corresponding normal or reverse switch control relay, and a circuit closed by the energization of the normal or reverse switch control relay for each switch for lighting the corresponding normal or reverse switch position indicator on the track diagram.

40. In a system of the entrance-exit type for governing the power operation of switches of a track layout providing different routes by the power operation of the track switches of such layout, control buttons manually operable to designate the entrance and exit ends of the different routes afforded by the track layout, switch control means for governing the power operation of each of the track switches to normal or reverse positions, route establishing circuit means responsive to the manual actuation of control buttons to designate the entrance and exit ends of any given route for energizing the switch control means associated with the switches in that route to cause operation of such switches to the proper normal or reverse positions, said switch control means also acting when energized to render ineffective such route establishing means with respect to all routes conflicting with said given route, an auxiliary switch control lever associated with each switch and provided with a neutral position and normal and reverse controlling position, circuit means associated with each auxiliary lever being normally inactive when such lever is in a neutral position and rendered active when such lever is in a normal or reverse controlling position for energizing the associated switch control means for causing the normal or reverse operation of the associated track switch only provided said route establishing circuit means is not energizing said switch control means for controlling said switch to a different position, and track circuit controlled switch locking means for preventing power operation of each switch while a train is approaching or passing over that switch, said locking means for each switch remaining effective after passage of a train if the corresponding auxiliary switch control lever is operated to change the position of the switch while the train is present and until said lever is restored to its neutral position.

41. In an interlocking system for railroads, a track layout including a plurality of track switches providing various routes between en-

trance and exit signal locations, a miniature track diagram of said track layout, manual control devices on said track diagram at points corresponding to said signal locations, normal and reverse switch control relays associated with each track switch for governing its operation to the normal or reverse position, route establishing means responsive to the operation of the manual control devices for the entrance and exit ends of any given route for energizing said normal and reverse relays as required to operate the track switches to establish that route, normal and reverse indicators for illuminating linear portions of said track diagram for each of the track switches to indicate visually the normal and reverse positions of such track switch, circuit means for energizing each of said indicators whenever the corresponding normal or reverse switch control relay for the associated switch is energized independently of the position of the switch, an auxiliary manually operable control device associated with each of the track switches and effective when operated from an inactive position to either a normal or reverse controlling position to energize the corresponding normal or reverse switch control relay providing the switch control relay for the opposite position is not already energized, a correspondence lamp for each switch, and circuit means for illuminating each of said correspondence lamps whenever its corresponding track switch is not in correspondence with the position to which that switch is being controlled either by the route establishing means or its auxiliary manual control device.

42. In an interlocking system for railroads, a track layout having a plurality of track switches operable to provide two optional routes between two signal locations, a control panel having a miniature track diagram on which said switches are represented to correspond with the actual track layout, a manually operable control button for each of said two signals on said panel at positions on the diagram corresponding to the actual location of said signals, auxiliary manually operable control means for each of said track switches, route establishing means controlled by the joint actuation of said two control buttons alone for effecting the operation of all of the track switches to at times set up a particular one of said two optional routes, and means responsive to the operation of the manually operable control means for that particular track switch required to be in different positions for the different optional routes to cause the operation of that switch to the position required for the other of said two optional routes and to also act on said route establishing means in a manner to thereby cause said route establishing means to effect the operation of the remaining track switches to positions required for said other optional route upon the actuation of the two control buttons for said two signal locations.

ROBERT M. PHINNEY.
